UNITED STATES PATENT OFFICE.

WILLIAM SENTURY McMATH, OF EL PASO, TEXAS.

JOB-PRESS STANDARDIZER.

1,213,520.

Specification of Letters Patent. Patented Jan. 23, 1917.

Application filed October 2, 1916. Serial No. 123,302.

To all whom it may concern:

Be it known that I, WILLIAM S. McMATH, a citizen of the United States, and a resident of El Paso, in the county of El Paso and State of Texas, have invented a new and Improved Job-Press Standardizer, of which the following is a full, clear, and exact description.

My invention has for its object to provide a standardizer for job presses which may be secured to the bed of a press, thereby permitting the use on the press of a chase from a smaller size press.

In most cases where presses of two sizes are used in a job press office, nearly all of the work may be done on the smaller presses, but a few of the larger presses are required for use on large work. When the small presses are in use and one of the larger presses is free, the chase for one of the smaller presses may with my standardizer be mounted on one of the larger presses. In this way practically all of the work is standardized on the smaller chases, and it is never necessary to change a form from a small chase to another chase for use on the larger press.

Additional objects of the invention will appear in the following specification, in which the preferred form of the invention is described.

In the drawings similar reference characters denote similar parts in all the views, in which—

Figure 1 is a perspective view of a press bed with my standardizer mounted thereon, parts being broken away to illustrate the construction; Fig. 2 is a front view of my standardizer, with a part broken away to illustrate the manner in which the movable pin is mounted; Fig. 3 is a plan view of Fig. 2; and Fig. 4 is a transverse sectional view of Fig. 3.

By referring to the drawings, it will be seen that my standardizer 5 has a fixed pin 6 at one end and a guideway 7 at its other end, a pin 8 being disposed in the guideway 7. This pin 8 is held yieldingly extended by means of a spring 9. The pin 8 may be locked in its outer position by means of a thumb-piece 10 which projects from the pin 8 into a bayonet slot 11, it being understood that when the thumb-piece 10 is pressed downwardly in the outer portion of the bayonet slot 11, the pin 8 will be pre-

vented from moving inwardly. The standardizer 5 has an inclined bottom 12 for engagement by fingers 13 which serve to support the bottom of the standardizer 5, the fixed pin 6 being disposed in an orifice 14 in a frame 16 at one side of a press-bed 17, it being possible to move inwardly the pin 8 by means of the thumb-piece 10, so that the pin 8 may then be disposed in an orifice 18 in the other side frame 19 of the press-bed. The fingers 13 are mounted on and extend forwardly from the press-bed in a manner well understood.

Spaced from its sides at points 20 and also spaced from the front of the standardizer at its top at 21, the standardizer is cut away rearwardly and downwardly, the end of this cut stopping at a point 22 at a considerable distance from the bottom of the standardizer. The said cut-away portions of the standardizer adjacent the points 20 permit the standardizer 5 to receive the lower beveled end 26^a of the chase 26. The standardizer also has a cut-away portion 23 which extends from the front 24 to the rear 25 of the standardizer, the rear portion of this cut 23 being inclined downwardly at 23^a, as best shown in Fig. 4 of the drawings. The cut-away portion 23 permits the standardizer 5 to secure a chase firmly in position, although the chase may be considerably warped.

The cuts and inclined portions of the standardizer are provided to facilitate the clamping of the lower portion of the chase 26, the upper portion of the chase 26 being secured in the usual manner.

Having thus described my invention, I claim as new and desire to secure by Letters Patent:

1. A job press standardizer having a lower edge for engagement by fingers on a press-bed, means for detachably securing the sides of the standardizer to the sides of the press-bed, the standardizer having a cutaway portion spaced from each side and extending from the front to the rear and through the top of the standardizer.

2. A job press standardizer having means by which it may be secured to a press bed, the standardizer from its top and from points spaced from its sides being cut away downwardly and rearwardly, there being an additional central cut-away portion in the standardizer which is spaced from the said

points, the additional cut-away portion extending from the front to the rear and through the top of the standardizer.

3. A job press standardizer having means by which it may be secured to a press-bed, the standardizer from its top and from points spaced from its sides being cut away downwardly and rearwardly, there being an additional central cut-away portion in the standardizer which is spaced from the said points, and an additional cut-away portion extending from the front to the rear and through the top of the standardizer.

4. A job press standardizer having means by which it may be secured to a press-bed, the standardizer from its top and from points spaced from its sides being cut away downwardly and rearwardly, there being an additional central cut-away portion in the standardizer which is spaced from the said points, and an additional cut-away portion extending from the front to the rear and through the top of the standardizer, the

standardizer being inclined downwardly at the rear of the said additional cut-away portion, the incline being at an angle to the incline of the first mentioned cut.

5. A job press standardizer having means by which it may be secured to a press bed, the standardizer from its top and from points spaced from its sides being cut away downwardly and rearwardly, there being an additional central cut-away portion in the standardizer which is spaced from the said points, the additional cut-away portion extending from the front to the rear and through the top of the standardizer, the standardizer being inclined downwardly at the rear of the said additional cut-away portion, the inclination being at an angle to the incline of the first mentioned cut.
